(57) CLAIM

The ornamental design for a sheet music holder, as shown and described.

DESCRIPTION

FIG. 1 is a front, top perspective view of a sheet music holder, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is another front, top perspective view of the sheet music holder, shown in an environment of use;
FIG. 10 is another rear, bottom perspective view thereof;
FIG. 11 is another front, top perspective view of the sheet music holder, shown in an environment of use;
FIG. 12 is another rear, bottom perspective view thereof;
FIG. 13 is another front, top perspective view of the sheet music holder, shown in an environment of use;
FIG. 14 is another rear, bottom perspective view thereof;
FIG. 15 is another front, top perspective view of the sheet music holder, shown in an environment of use; and,
FIG. 16 is another rear, bottom perspective view thereof.
The evenly space broken lines are shown for the purpose of illustrating both parts of the sheet music holder as well as environmental subject matter. None of the broken lines form part of the claimed design.

1 Claim, 16 Drawing Sheets
